[57] CLAIM

The ornamental design for sidewalls for a bottle, as shown and described.

DESCRIPTION

FIG. 1 is a perspective view of sidewalls for a bottle showing our new design;

FIG. 2 is a left side elevational view thereof;

FIG. 3 is a right side elevational view thereof;

FIG. 4 is a front view thereof;

FIG. 5 is a back view thereof;

FIG. 6 is a top elevational view thereof; and,

FIG. 7 is a bottom plan view thereof.

The broken lines showing the bottom of the bottle and the neck are for illustrative purposes only and do not form part of the claimed design.

1 Claim, 2 Drawing Sheets
